(57) **CLAIM**

The ornamental design for a display for dialysis machine, as shown and described.

DESCRIPTION

FIG. 1 is a perspective view of the display for dialysis machine showing the top, front and left sides thereof;

FIG. 2 is a perspective view of the display for dialysis machine showing the top, front and right sides thereof;

FIG. 3 is a perspective view of the display for dialysis machine showing the top, rear and right sides thereof;

FIG. 4 is a perspective view of the display for dialysis machine showing the top, rear and left sides thereof;

FIG. 5 is a front side view thereof;

FIG. 6 is a left side view thereof;

FIG. 7 is a right side view thereof;

FIG. 8 is a top side view thereof; and,

FIG. 9 is a rear side view thereof.

The broken line representations in the figures are for illustrative purposes only and form no part of the claimed design.
